[57] CLAIM

The ornamental design for a hair accessory support rack, as shown and described.

DESCRIPTION

FIG. 1 is a perspective view of a hair accessory support rack in accordance with my new design;

FIG. 2 is a right side elevational view thereof;

FIG. 3 is a left side elevational view thereof;

FIG. 4 is a rear elevational view thereof;

FIG. 5 is a plan view thereof, the bottom view being a mirror image thereof; and,

FIG. 6 is a front elevational thereof.

FIG. 1 - A

FIG. 2 - B

FIG. 3 - C
